UNITED STATES PATENT OFFICE.

JOHN REID, OF LONDON, ENGLAND.

AIR HEATERS OF STEAM-BOILER FURNACES.

Application filed April 19, 1921. Serial No. 462,675.

To all whom it may concern:

Be it known that I, JOHN REID, a subject of the King of Great Britain and Ireland, residing at London, England, have invented

5 Improvements Relating to Air Heaters of Steam-Boiler Furnaces, of which the following is a specification.

This invention has reference to air heaters for forced draft furnaces, the object 10 being to facilitate repairs, inspection, cleaning or replacement, especially in the case of heaters of marine boiler furnaces.

By the adoption of a construction facilitating the introduction of standardized 15 withdrawable tube boxes, the said construction, moreover, being adapted to provide large air entrances and exits, and for the easy flow of air at slow speed, and its smooth and even distribution to furnace fronts.

20 According to the present invention the air heater is built up of standardized sections each capable of bodily removal from the flue space in which it is located and the walls of said space are formed with openings 25 communicating with air ducts located in such positions as to pick up available heat from the boiler, the arrangement being such that when the heater is in position the air from the fan will pass to the heater, 30 follow the proper course therethrough and pass therefrom to ducts leading to the furnace front or fronts.

35 Preferably separate standardized sections of the heater each comprise tube plates with connecting tubes through which the gases pass, and also, comprise side and end walls. Each section is mounted on suitable ledges or supports in the smokebox of the corresponding furnace above the level of the 40 smoke tubes and may be secured by bolts passing through flanges on the outer ends of its side walls and tube plates and a cover plate. Each section is divided by dia- 45 phragms so as to give air, admitted at the upper front side from a suitable air trunk connected to a fan, a zig-zag course through the section to lateral outlets at the bottom communicating with ducts arranged around and between the smoke boxes and leading 50 the heated air to the furnaces. Where outlets between adjacent sections face each other a depending partition may be ar- ranged in the head of the common duct.

55 Referring to the accompanying drawings illustrating one embodiment of the invention, Fig. 1 is a sectional elevation in two

planes on the line C—C (Fig. 2) and with parts removed of an air heater in three sections applied to a marine boiler having three furnaces;

60 Fig. 2 is a section on the line A A Fig. 1;

Fig. 3 is a section on the line B B Fig. 1;

Fig. 4 is a side view of one section of the heater withdrawn and suspended by chains;

Fig. 5 is a detail view showing to a larger 65 scale and in section the connection of the air inlet duct to a heater section; and

Fig. 6 is a detail view illustrating the air heater supports and the air outlet ducts.

The three smoke boxes *a a* have at each 70 side air ducts *b, b* and, in the upper part of

each smoke box above the level of the smoke tubes *a¹* of the boiler, an air heater section is supported on angle irons *c* fixed to the smoke box walls which extend up to the 75 top of the heater sections and form guides

therefor and also serve to stiffen the back plate of the smoke box against warping.

Each heater section comprises upper and lower tube plates *d* connected by smoke 80 tubes *e*, a back wall *f*, side walls *g* formed at the bottom with air outlet apertures *h*,

and a front cover plate *i* having at its upper part an air inlet aperture *j*; *k* is a dia- 85 phragm to ensure the air taking a long

course amongst the tubes and *l* (Fig. 3) is an inclined partition to prevent the forma- 90

tion of eddies in the air current. The tube plates *d* and side walls *g* are flanged at the 95 front and the front plate of the smoke box

is formed with openings so that the section 100 may be slid in and out on their supports *e*,

bolts *m* (Fig. 5) passing through the cover 105 plate *i*, the flanges referred to and the front plate of the smoke box securing each sec-

tion when in position. Across the front of 110 the upper parts of the heater sections ex-

tends an air supply duct *n* (Figs. 2, 3 and 5) which is secured to the cover plates *i* by 115 bolts *o* around the apertures *j*; flanged

120 mouthpieces *p* are attached to the duct, the flanges being adapted to extend into the 125 openings *j* to retard leakage of air. The

air duct *n* communicates with an air trunk 130 not shown that extends to the back of the 135 boiler and is connected to a fan. *n¹* are

curve baffles to direct air into sections of 140

the heater.

The smoke box walls have apertures *q* 145 (Fig. 6) which coincide with the apertures

h in the heaters and through which the heated air passes into the ducts *b* that lead to

the hollow furnace fronts indicated at α Fig. 3; r are depending partitions between opposed apertures q for smoothly diverting the air down into the ducts b .

5 As will be understood in passing through the ducts b air is further heated since heat from the furnace gases in the smoke boxes will be transmitted through the separating walls to the air.

10 What I claim is:—

1. An air heater of a steam boiler comprising a removable heater section constructed as an interchangeable standardized unit, means for loosely supporting said section in the flue space of the boiler, means for detachably securing said section in position and ducts leading air to and from said section.

2. An air heater of a steam boiler comprising a number of standardized heater sections each constructed as an interchangeable unit, means for independently supporting each such section in the flue space of the boiler, means for independently and detachably securing each section in position, air inlets and air outlets pertaining to the respective sections, an air supply duct common to the several sections and connected to said inlets and air ducts separated by walls from the flue space and connected to the outlets of the sections.

3. A removable and interchangeable standardized box-like air heater section comprising upper and lower tube plates, tubes extending through said tube plates, a back wall connecting the tube plates, side walls connecting said tube plates and having air outlet apertures and a front cover plate having an air inlet aperture, the whole section being adapted to fit a flue space in which it is supported.

4. A removable and standardized interchangeable box-like air heater section com-

prising upper and lower tube plates, tubes extending through said tube plates, a back 45 wall connecting said tube plates, side walls connecting said tube plates and having air outlet apertures, outwardly extending flanges at the front of said tube plates and side walls, a cover plate adapted to extend 50 over said flanges and having an air inlet aperture the whole section being standardized and adapted to fit a flue space in which it is supported and to be secured in place by bolts extending through the cover plates 55 and said flanges.

5. The combination with a marine boiler of an air heater which or each section of which is standardized and capable of bodily removal from the flue space in which it 60 is located whilst the walls of said space are formed with openings communicating with air ducts located in such positions as to pick up available heat from the boiler, the arrangement being such that when the 65 heater is in position the air from the fan will pass to the heater, follow the proper course therethrough and pass therefrom to ducts leading to the furnace front or fronts.

6. The combination with a marine boiler 70 having at least two furnaces of an air heater in separate interchangeable standardized sections each comprising tube plates with connecting tubes through which the gases pass and mounted on suitable ledges 75 or supports in the smokebox of the corresponding furnace above the level of the smoke tubes an air trunk connecting a fan with an air inlet at the front of each section, lateral outlets at the bottom of each 80 section and communicating with ducts arranged around and between the smoke boxes and leading the heated air to the furnaces.

Signed at London this 16th day of March, 1921.

JOHN REID.
